UNITED STATES PATENT OFFICE.

CASSIUS CLAY PALMER, OF NEW YORK, N. Y.

REFRIGERATING APPARATUS.

No. 839,190.

Specification of Letters Patent.

Patented Dec. 25, 1906.

Application filed March 28, 1905. Serial No. 262,603.

To all whom it may concern:

Be it known that I, CASSIUS CLAY PALMER, a citizen of the United States, and a resident of the city of New York, borough of Manhattan, county and State of New York, have invented a certain new and useful Improvement 5 in Refrigerating Apparatus, of which the following is a specification.

This invention relates to refrigerating apparatus and the means whereby said apparatus is operated either when in a stationary position or upon a refrigerating-car when the same is moving.

It consists of certain novel parts and combinations of parts particularly pointed out in the claims concluding this specification.

I have shown in the accompanying drawings my invention in the form which is at present preferred by me, although it will be understood that various changes and modifications may be made therein without departing from the spirit of my invention and without exceeding the scope of the concluding claims.

Figure 1 shows a cross-sectional elevation through the chamber in the end of a car containing my invention. Fig. 2 is a longitudinal elevation of the end of the car. Figs. 3, 4, and 5 show details of a form of the pawl-and-ratchet device used in my invention.

The chamber in the end of the car containing the refrigerating apparatus may be referred to as A, the chill-room or cold-storage chamber as B.

1 is a rotary compressor upon a shaft 2, mounted in bearings in a frame 3, which is secured to the base 4 upon the floor of the car. From the compressor a pipe 5 leads into the pipes 6 6, &c., within the condenser 7. The pipe 8 leads from the said pipes 6 6, &c., into the refrigerator or brine-cooler 9, and from this refrigerator or brine-cooler the pipe 10 leads back to the compressor. Thus is formed a complete circuit from the compressor through the condenser and refrigerator and return to the compressor.

11 is a pump suitably secured to the wall of the chamber A. From this pump leads a pipe 12, which enters into and coils around within the refrigerator 9. Emerging therefrom it passes through the partition between the chambers A and B, extends through said chamber B, and returns to the pump 11. Through this pipe circulates the brine or other suitable refrigerating material.

In order that the condenser-pipes 6 6, &c., may be kept cool, I place above said pipes a tank 13, containing water and having outlets 14 14, &c., through which the water may fall upon the pipes. To further aid in cooling said pipes, I place a fan 15 beneath them, which fan is caused to revolve by means of a belt 16, which extends to and is driven by the shaft 2. The brine-pump 11 is also driven from the shaft 2 through the belt 17 and shaft 18.

19 is a receptacle containing the lubricant for the rotary compressor, said lubricant being fed through the pipes 20 20^a, and after circulating through the compressor a portion of it is forced out into the pipe 5 and finds its way by means of the pipe 20^b back to the receptacle 19.

I will now proceed to describe the principal feature of my invention, which lies in the novel means for automatically driving the compressor, irrespective of the direction in which the car may be traveling, so that the compressor may always rotate in one direction without the necessity of employing an attendant to operate it. The compressor may be operated either from the car-axle or from the oil-engine 21 within the car. The oil-engine operates the compressor through the shaft 22, to which is affixed the sprocket-wheel 23, the shaft 2, to which is affixed the sprocket-wheel 24, and the chain belt 25, which engages with said sprocket-wheels. The oil-engine will of course operate the compressor always in the one desired direction—

that is, in the direction of the arrows—the fluid entering through the pipe 10 and departing to the condenser by the pipe 5. When it is desired to run from the car-axle, the oil-engine may be stopped and the clutch mechanism 26 brought out of engagement with the shaft 22, so that the sprocket-wheel 23 may run idle. The clutch mechanism 27 upon the shaft 28, which revolves in bearings in the frame 3, may then be thrown into engagement, causing said shaft to revolve from the car-axle by means of the belt 29, which is held in position and has its tension regulated by the idler-rollers 30 and 30^a, said rollers being drawn together by means of the spring 31, thus compensating for the motion of the springs upon which the car rests, the turning of curves, or any other variations between the axle of the car and the shaft 28.

The shaft 28 has mounted on one end there-

of the sprocket-wheel 32, which is free to revolve upon said shaft and is held thereon by any suitable means—as, for example, the collar 33. Said sprocket-wheel carries with it 5 the pawls 34 34, which are suitably secured thereto. Keyed to the shaft 28 is a ratchet-wheel 35.

36 is a plate carrying projections 36^a 36^a. This plate bears against the shoulder 28^a of 10 the shaft, and between said plate and ratchet-wheel is interposed any suitable frictional substance 37. Extending through the pawls is a pin 38, which on one side of the pawl rides upon the plate 36, while on the other 15 side it is borne upon by the spring 39, attached to the sprocket-wheel.

40 is a spring bearing against the ratchet-wheel and interposed between it and the frame 3.

20 41 is a stop or pin affixed to the sprocket-wheel.

A chain belt 42 extends from the sprocket-wheel 32 to the sprocket-wheel 43 upon the shaft 2. The other end of the shaft 28 has 25 mounted thereon a gear-wheel 44, which is free to revolve on said shaft. Affixed to said gear-wheel are the pawls 45 45.

46 is a ratchet-wheel keyed to the shaft 28, and 47 is a plate carrying projections 47^a 47^a 30 and bearing against a shoulder 28^b of the shaft. Between said plate and ratchet-wheel is interposed a frictional substance 48.

The pawls 45 have passing through them a pin 49, the projection of this pin on one 35 side riding on the plate 47 and on the other side being borne upon by a spring 50. A spring 51 is interposed between the frame 3 and the ratchet-wheel and bears against said wheel.

40 52 is a pin or stop.

A gear-wheel 53 upon the shaft 2 meshes with the gear-wheel 44.

It is to be observed that the rotary compressor must always operate in the direction 45 of the arrow, so that the fluid to be compressed may enter by means of the pipe 10, be compressed, and travel to the condenser by pipe 5. We will assume now, taking Fig. 1 of the drawings, that the car is traveling toward us. The belt 29 will then revolve in the direction indicated by the arrow and of course will revolve the shaft 28 in this direction. This operation will cause the ratchet-wheel 35 to revolve and frictionally engage 50 with the plate 36. Said plate will then be carried around until the projections 36^a 55 strike the stop 41. The pawls 34 34, which up to this point have been held out of operation by reason of the pin 38 therein riding on the plate, will be pressed by means of the spring 39 into engagement with the ratchet-wheel, and by means of such engagement the sprocket-wheel 32 will be driven and will drive the chain belt 42 and sprocket-wheel 43, 60 thus causing the shaft 2 to operate the rotary 65

compressor in the desired direction. In the meantime the revolution of the shaft 28 will cause frictional engagement between the ratchet-wheel 46 and plate 47, and said plate, having the pin 49 of the pawls riding thereon, 70 will gradually raise said pawls out of engagement with the ratchet-wheel, and the projections 47^a coming in contact with said pawls will hold them out of the path of the ratchet-wheel. The shaft is then free to revolve 75 without operating the gear-wheel 44. Reversing the direction of travel of the car will cause the belt 29 to operate the shaft 28 in the reverse direction. This operation will throw the pawl-and-ratchet mechanism for 80 driving the sprocket-wheel 32 out of operation, so that said wheel may run idle on the shaft and will cause the pawl-and-ratchet mechanism at the other end of the shaft to engage and drive the gear-wheel 44, which 85 in turn will drive the gear-wheel 53, and thus rotate the shaft 2 to drive the rotary compressor in the proper direction.

It will be seen that the pawl-and-ratchet mechanism I have above described for throwing either the gear-wheel 44 or the sprocket-wheel 32 into and out of driving operation is similar, Figs. 1 and 3 illustrating the mechanism driving the sprocket-wheel 32, while Fig. 5 shows it out of operation with relation 95 to the gear-wheel 44.

It is of course to be understood that the above-described pawl-and-ratchet mechanism is shown simply as one means of accomplishing the driving. Other means may be 100 employed with the same results.

Having thus described my invention, what I claim, and desire to secure by Letters Patent, is—

1. The combination with a car, of refrigerating apparatus mounted thereon, a rotary compressor, driving connections between the compressor and the car-axle, means coöperating with the driving connections whereby the compressor will be driven in one direction irrespective of the direction of movement of the car, an engine, power connections between the engine and the compressor, and means for shifting said power connection into and out of driving engagement with the engine.

2. In combination, a car, a rotary compressor, a shaft for said compressor, a second shaft driven from the car-axle, a plurality of driving-wheels carried by said second shaft 110 adapted to coöperate with the driving-wheels carried by the compressor-driving shaft and means whereby one set of said driving-wheels may operate to drive the compressor when the car is traveling in one direction, and the other set of driving-wheels operate to drive the compressor when the car is traveling in the opposite direction.

3. The combination with a car, of a rotary compressor carried thereby, a shaft for said 130

compressor, a second shaft in driving engagement with the car-axle, by means of a belt, said belt being guided between idler-rollers, a plurality of driving-wheels carried by said 5 second shaft adapted to drive the wheels on the compressor-shaft, and mechanism actuating one of said driving-wheels to drive the compressor when the car is running in one direction, and operating to cause the other of to said driving-wheels to drive the compressor

when the car is running in the opposite direction.

In testimony whereof I have signed my name to this specification in the presence of two subscribing witnesses.

CASSIUS CLAY PALMER.
